UNITED STATES PATENT OFFICE

JOHN E. JOHNSON, OF LITCHFIELD, MINNESOTA

MIXING MACHINE FOR VISCOUS AND GRANULAR MATERIALS

Application filed July 23, 1928. Serial No. 294,707.

This invention relates to machines for mixing viscous liquids with granular materials and it relates particularly to such a machine, whereby molasses can be mixed with grain 5 to be used for feed purposes.

It is the object of this invention to provide a novel and improved machine for mixing molasses or similar viscous liquid with grain or similar granular material, whereby a thorough and efficient mixture may be cheaply and readily obtained without necessitating the heating of the viscous liquid.

To this end, the invention consists in the novel parts and novel combinations of parts 15 hereinafter defined in the claims, and described in the following specification, made in connection with the accompanying drawings, wherein like reference characters refer to the same or similar parts throughout the 20 various views and, in which,

Fig. 1 is a view in end elevation of the machine, looking towards the rear end of the machine;

Fig. 2 is a view in side elevation of the machine looking at the right side of the machine as shown in Fig. 1; certain of the parts being broken away to more clearly show the construction thereof;

Fig. 3 is a vertical section taken on the line 30 3—3 of Fig. 2, as is indicated by the arrows;

Fig. 4 is a vertical section taken on the line 4—4 of Fig. 2, as is indicated by the arrows;

Fig. 5 is a vertical section taken substantially on the line 5—5 of Fig. 1, as is indicated by the arrows, certain of the parts being broken away, and

Fig. 6 is a vertical section taken on the line 6—6 of Fig. 5, as is indicated by the arrows.

Referring to the drawings, a suitable supporting frame is provided comprising the four legs 7, upper cross bars 8 and longitudinal cross bars 9 adjacent the lower ends of the legs. The legs 7, cross bars 8, and longitudinal bars 9 are all of angle bar construction, and extending transversely between the longitudinal bars 9 are a pair of channel bars 10 adjacent the forward end of the frame, and a pair of cross bars 11 adjacent the rear end of the frame. A substantially horizontally extending cylindrical drum 12 is sup-

ported by suitable brackets 13 on the upper cross bars 8 of the frame, so that the drum extends longitudinally of the frame. The drum 12 carries suitable bearings 14 and 15 at its forward and rear ends respectively, and a square shaft 16 centrally disposed in the drum 12 has rounded portions at its ends which are journaled within the bearings 14 and 15. The shaft 16 projects forwardly from the drum 12 and has a pulley 17 secured to its forwardly projecting portion. The drum 12 at its upper side adjacent its forward end is provided with a substantially square opening 12^a and a slotted opening 12^b. The slotted opening 12^b is disposed substantially centrally of the upper side of the drum, as is best shown in Fig. 3, while the opening 12^a is disposed at one side of the center of the upper surface of the drum. A casting 18 fits over the openings 12^a and 12^b at the rear upper side of the drum 12 and the casting is bolted or otherwise secured to the drum. A reinforcing rod 19 may also be used for firmly positioning the casting in place and the rod is illustrated as running through the casting and through the brackets 13 securing the drum to the frame. The casting 18 may be considered as comprising a small cylindrical portion 18^a joined to a large casing portion 18^b by means of an arcuate web 18^c which fits against the central top portion of the drum 12, a small web 18^d which extends horizontally and a vertical web 18^e which forms a portion of the rear wall of the casting. The cylindrical portion 18^a has a horizontally disposed cylindrical bore therein which extends parallel to the shaft 16 and within this bore is disposed a tube 20 open at both ends, and having an enlargement at its rear end forming a small chamber 20^a. The enlarged portion at the rear end of the tube 20 forms shoulders which abut the rear side of the cylindrical portion 18^a, while the forward end of the tube 20 is closed by a cap 21 screw threaded on to the tube. A slot 18^f extends vertically downwardly through the cylindrical portion 18^a and the web 18^e to communicate with the slotted opening 12^b in the drum 12. The tube 20 has a slot 20^b cut through its lower wall inwardly from the rear end of the

casting 18 and this slot 20^b is in alinement with the slots 18^c and 12^b. A sleeve 22 fits within the bore of the tube 20 and is closed at its forward end by a plug 23 carrying a stud 24 which fits through the cap 21 and acts as a pivot for rotation of the sleeve 22. The stud 24 and plug 23 are held in the sleeve 22 as by means of a short pin 25. Two nuts 26 on the outer end of the stud 24 jam against each other and prevent the removal of the sleeve from the tube 20. The sleeve 22 has a slot 22^a cut through its bottom wall and this slot is adapted to be alined with the slot 20^b. Small holes 22^b are cut through the walls of the sleeve 22 to afford communication between the chamber 20^a and the interior of the sleeve. A nut 27 screw threaded in the rear end of sleeve 22 forms a packing nut for closing the rear end of the tube 20 and carries an arm 28 projecting upwardly therefrom, and bent at right angles adjacent its upper end to fit over the top edge of the web 18^e. The web 18^e is segment-shaped relative to the axis about which the sleeve 22 may turn, and has a projecting finger 18^g at its left upper end, as viewed in Fig. 1, to limit the movement of the rod 28. The upper edge of the web 18^e is notched to form graduations which will indicate relative alinement between the slots 22^a and 20^b of the sleeve and the tube respectively.

As is illustrated in Fig. 1, a tank 29 is provided at one side of the frame holding the drum 12 and this tank will be used as a supply tank for molasses or other viscous liquid to be used during the operation of the machine. A conduit 30 runs upwardly from the tank 29 and is connected to a rotary pump 31 which, in turn, discharges to a conduit 32 running upwardly to a molasses meter 33. The meter 33 is of standard construction and will register the amount of molasses or other viscous liquid running through the conduit 32. The conduit 32 extends upwardly from the molasses meter and is connected by a suitable coupling at its upper end to the enlarged outer portion of the tube 20 so that the liquid carried by the conduit will be admitted to the chamber 20^a when the pump 31 is in operation. A pressure gauge 34 is interposed in the conduit 32 at a suitable point to indicate the pressure of the liquid in the conduit. A downward extension 35 projects from the conduit 32 downwardly from adjacent the discharge point of the pump 31 to the top of the tank 29 and the extension 35 is provided with a control valve 36 which is adapted to open or close the extension.

With the construction thus far described, it will be apparent that when the valve 36 is closed and the pump 31 is set in operation, that molasses or other viscous liquid held within the tank 29 will be forced upwardly through the conduit 30, through the pump 31, through the conduit 32 and molasses meter 33

to the chamber 20^a, whereupon when the handle 28 is swung so that the slots 22^a and 20^b are alined, or are in partial alinement, the molasses or other liquid will run through the openings 22^b into the interior of the sleeve 22, whereupon the molasses will be discharged in a narrow ribbon through the slots 22^a and 20^b and downwardly through the opening 18^c and through the slotted opening 12^b into the interior of the drum 12. The molasses will thus be discharged into the upper portion of the drum 12 adjacent its forward end in a thin ribbon which will be parallel to the shaft 16.

The casing portion 18^b of the casting 18 forms a hopper 18^h at its upper end and this hopper leads downwardly into a large cylindrical portion of the casing within which a horizontal shaft 37 is journaled. The shaft 37 projects outwardly from the forward side of the casing portion 18^b and has a pulley 38 secured thereto which is adapted to be driven from any source of power by means of the belt 39 or by other suitable means. A wheel 40 secured to the shaft 37 works within the cylindrical portion of the casing and is provided with two sides 40^a, a cylindrical drum like portion 40^b radially spaced outwardly from the center of the shaft 37 and a plurality of radial wings 40^c which extend between the sides 40^a outwardly from the cylindrical portion 40^b. The wings 40^c co-operating with the sides 40^a, and the outer surface of the cylindrical portion 40^b, will form a series of compartments for picking up and distributing grain or other granular material which may be thrown into the hopper 18^h. Grain is adapted to be carried by the said compartments downwardly from the hopper to a passage 18^k which projects downwardly below the cylindrical portion of the casing portion 18^b and communicates with the interior of the drum 12, through the opening 12^a adjacent the forward end thereof. The grain or other material will thus be charged into the drum at one side of the point where the molasses or similar viscous material is charged into the same. It should be here noted that the length of the openings 12^a and 12^b longitudinally of the drum 12 are the same.

The square shaft 16 has a plurality of radial rods 41 secured thereto. Each of these rods are screw threaded at their inner ends and project through openings provided in the shaft 16 and are held thereon by nuts 42, one of which is placed at either side of the shaft. The rods 41 are longitudinally spaced on the shaft 16 and are circumferentially spaced so that each rear rod is set at a 45° angle behind each adjacent forward rod relative to the direction that the shaft 16 is adapted to turn as indicated by the arrow Fig. 3. As the shaft is rotated, therefore, the rods will successively follow each other

in their action on the material held within the drum 12 from the forward end of the drum to the forward end thereof.

At its rear end, the drum 12 is provided with a discharge opening 12^c and as is best illustrated in Fig. 4, this opening is formed at the lower left quadrant of the rear end of the drum. Guides 43 are secured to the rear end of the drum at either side of the opening 12^c, and mounted within these guides is a plate 44 having secured thereto an operating rod 45, which projects upwardly through a collar 46 secured to the rear end of the drum above the opening 12. A set screw 47, screw 15 threaded within the collar 46, is adapted to act on the rod 45 to hold the plate 44 in a desired position projecting upwardly from the bottom of the opening. The discharge port of the drum formed by the opening 12^c and plate 44 can, therefore, be controlled by operation of the rod 45 and the set screw 47.

A casing 48 secured to the rear end of the drum 12 fits over the discharge port and projects downwardly therefrom, and is connected, in turn, to a second casing 49 which leads into the central portion of a blower casing 50 suitably supported by brackets 51 from the forward cross bars 11. A blower shaft 52 is suitably journaled within the blower casing 50 and carries a blower fan 53 within the casing 50. The blower casing 50 has a tangential discharge port to which a pipe 54 is secured, which pipe may be carried to any point where it is desired to discharge the mixed material, such for example, as a loading platform or elevator, (not illustrated). The fan 53 will act to assist the rods 41 in drawing the mixture of granular material and viscous liquid through the drum 12 and casings 48 and 49. To regulate the pressure exerted by the fan 53, a suitable damper is provided in the casing 48. While this damper may be variably formed, in the illustrated drawings, it is shown as consisting of 45 guide strips 55 mounted on the rear side of the casing 48 at either side of an air admission opening 48^a. A plate 56 is slidably mounted within the guide strips 55 and has a slot in its central portion through which a stud 57, carrying a wing nut 58, projects. By loosening wing nut 58 and by raising or lowering the plate 56, the opening 48^a may be more or less opened to vary the amount of air that may be admitted through the openings 48^a to the casing 48, and to the fan 53. Accordingly, the draft of air caused by the fan through the drum 12 may be varied by regulation of the damper in the casing 48.

A motor bracket 59 of angular shape and having an arcuate web at one side thereof, is mounted on the forward cross bars 10 of the frame. Slots are provided in the base portion of the bracket 59 and nutted bolts 60 extending through the bars 10 project through 65 the slots in the base. Studs 61 project out-

wardly from the corner of the bracket 59 through the vertical flanges of the right longitudinal bar 9, as viewed in Fig. 2, and these studs carry nuts at the outer sides of the bar 10. It will be seen that by loosening the 70 nutted bolts 60 and the nuts on the studs 61 that the bracket 59 may be laterally adjusted relative to the frame carrying the drum 12. A motor 62 having arms 63 secured thereto is mounted on vertical bars 64 by means of bolts 65 which project through the arms 63 and the bars 64, and also through vertical slots 59^a cut in the vertical side of motor bracket 59. The bolts 65 are provided with nuts at the outer side of the bracket 59. The bars 64 are 75 bent horizontally at their upper ends and studs 66 extend through the horizontally bent portions of the bars and also through outwardly projecting lugs 59^b adjacent the upper end of the vertical side of the motor bracket 59. These lugs have openings which are screw threaded to receive studs 66. At either side of the horizontal portions of the bars 64, the studs 66 have nuts 67 which bear against the bars. It will be seen that by 80 loosening the nuts carried on the bolts 65, and by loosening the nuts 67 and by turning the studs 66 that the motor 62 and bars 64 can be raised or lowered respective to the motor bracket 59. The motor, therefore, is capable 85 of adjustment vertically and transversely of the frame.

The motor has a motor shaft 68 which projects both forwardly and rearwardly from the motor proper and carries at its forward 100 end a pulley 69, and at its rear end a pulley 70. A belt 71 runs over the pulleys 69 and 17, while a belt 72 runs over the pulley 70 and also over a pulley 73 secured to the forward end of the blower shaft 52. By proper adjustment of the motor vertically and laterally of the frame, the belts 71 and 72 can be 105 properly tensioned so that both the shaft 16 and the fan shaft 52 may be driven from the motor.

In operation, grain or similar material will be fed into the hopper 18^a, while molasses or similar viscous liquid will be fed under pressure through the pipe 32 into the sleeve 22. The molasses or similar viscous material may be charged into the sleeve 22 in cold state if so desired. The quantity of viscous liquid used will be shown by the molasses meter 33, while the pressure under which the viscous liquid is carried upwardly 110 to the sleeve 22 will be indicated by the pressure gauge 34. By manipulation of the rod 28, the valve formed by the tube 20 and the sleeve 22 may be so adjusted that a desired quantity of molasses or similar viscous liquid 115 may be charged into the drum 12 at the same time that a desired quantity of grain or similar granular material is charged into the drum through the hopper 18^a and by means of the wheel 40 which will be rotated by means 120 125 130

of the power applied to the belt 39. The molasses will be discharged into the drum in a thin ribbon which is of the same length longitudinally of the drum as the mass of grain charged into the drum through the opening 12^a. The shaft 16 will be rotated in the direction as indicated by the lower arrow Fig. 3, when the motor 62 is in operation and, accordingly, the rods 41 at the forward end of the shaft 16 will first strike the molasses and carry the same downwardly and to the right, as indicated in Fig. 3, into the mass of grain as it is discharged into the drum. The molasses, accordingly, will almost immediately upon its entrance into the drum be mixed with the grain before the molasses has an opportunity to run downwardly to the bottom of the drum, and accumulate there. As the shaft 16 continues to rotate, successive arms 41 rearwardly of the forward end of the shaft will strike the grain and molasses and will more thoroughly admix the same and will at the same time advance the mixture rearwardly to a position where other successive rearward arms 41 will strike the same. When the machine is first set in operation, the operating rod 45, controlling the movement of the plate 44, will be so set that the opening 12^c will be almost entirely closed. Also the plate 56 controlling the opening 48^a will be preferably lowered so that a large quantity of air can be supplied to the blower 53 through the opening 48^a, thereby preventing the blower from exerting much force to pull the mixture through the drum 12. When sufficient grain and molasses have been admitted to the drum 12 so that the drum is approximately half filled with the mixture, the operating rod 45 will be lowered to open the discharge port at the rear end of the drum and at the same time the plate 56 will be raised to almost completely close the opening 48^a. The mixture of grain and molasses will thus be discharged from the discharge port at the rear end of the drum into the casing 48, whereupon the same will run downwardly through the casing 49, to the blower casing 50 and will there be forced upwardly by the blower to discharge through the conduit 54. The rods 41 on the shaft 16 acting with the blower will force the material from the discharge port. If for any reason the mixture is discharged from the discharge port of the drum before it has been thoroughly admixed, the plate 44 can be raised by means of the rod 45 to raise the lower edge of the discharge port and partially close the opening 12^c, and also the plate 56 can be lowered to permit a greater draft into the blower through the opening 48^a, thereby decreasing the force exerted by the blower in pulling the mixture through the drum. When the desired quantity of molasses and grain or other material has been mixed and it is desired to stop the mixing

machine, the molasses or similar viscous material may be drained from the conduit 32, through the extension 35 back into the tank 29 by merely opening the valve 36.

The machine will be used chiefly at feed mills or on large farms where it is desired to mix a large quantity of grain or similar material with molasses or similar material for feed for stock, poultry etc. For different kinds of stock and poultry, it is desirable to mix different proportions of molasses with the grain. Also at different times of the year, more or less molasses will be mixed with the feed than at other times of the year. With the present machine, any desired quantity of molasses or similar viscous material may be mixed with the grain or other feed used and the mixture can be made without heating the molasses or other viscous material.

The machine has been demonstrated in actual practice and has been found to be very successful for the purposes set forth. The machine is quite simple in its construction and the operation thereof is easily understood.

It will of course, be understood that various changes may be made in the form, details, arrangement and proportions of the various parts without departing from the scope of the present invention.

What is claimed is:

1. A machine for mixing granular material with a viscous liquid, comprising, a substantially horizontally disposed drum, a shaft mounted within said drum, means for rotating said shaft in one direction, means for charging viscous liquid in a thin ribbon parallel to said shaft into the forward end of said drum, means for charging granular material into the forward end of said drum ahead of the point where said liquid is charged into the drum relative to the rotation of said shaft, means for regulating the quantity of viscous liquid discharged into the drum during any interval of time, and indicating means to show the quantity of viscous liquid being discharged into the drum.

2. A machine for mixing granular material with a viscous liquid, comprising a substantially horizontally disposed drum, a shaft mounted within said drum for rotation in a certain direction, means for charging viscous liquid in a thin ribbon parallel to said shaft into the forward end of said drum at approximately the upper central portion thereof, means for charging granular material into the forward end of said drum at one side of the top of the drum, the point of discharge of the granular material being spaced in the direction of rotation of said shaft relative to the point of discharge of the viscous liquid, a plurality of radial arms mounted on said shaft, and means for rotating said shaft so that the arms at the

- forward end of the shaft will first move against the ribbon of viscous liquid to carry the same against the granular material before the viscous liquor has fallen to the bottom of the drum, said arms being adapted to mix the liquid with the granular material and to carry the mixture toward the rear end of the drum, said drum having a discharge port rearward from its forward end. 5
- 10 3. A machine for mixing granular material with a viscous liquid, comprising a substantially horizontally disposed drum, a shaft mounted within said drum, means for rotating said shaft in one direction, means 75 at the top of said drum for charging viscous liquid in a thin ribbon parallel to said shaft, into the forward end of said drum, means for charging granular material into the forward end of said drum at a point spaced 20 slightly in the direction of rotation of said shaft relative to the point of discharge of said viscous material and means on said shaft for carrying the liquid as discharged into the granular material before the liquid falls 25 to the bottom of the drum and for mixing the liquid and granular material and for moving the mixture toward the rear end of the said drum, the said drum having a discharge port rearwardly from its forward end. 85
- 30 4. A machine for mixing granular material with a viscous liquid, comprising a cylindrical drum extending substantially horizontally, means for charging granular material into the forward end of said drum, 90
- 35 a tube mounted adjacent the rear end of said drum and having a slot therein in communication with the said drum, a sleeve mounted within said tube and rotatable therein, and having a slot adapted to be brought 95
- 40 more or less into registry with the slot in said tube, means for supplying viscous liquid to the interior of said sleeve, a shaft in said drum, means for rotating said shaft and means on said shaft adapted to first strike 100
- 45 said liquid as it is charged into said drum and to carry the liquid into the granular material charged into the drum, to mix the two materials together and to carry the same toward the rear end of the drum. 105
- 50 5. A machine for mixing granular material with a viscous liquid, comprising a cylindrical drum extending substantially horizontally, a casing mounted at the forward end of said drum above the same and 110
- 55 having communication with said drum, means in one portion of said casing for receiving and discharging granular material into the forward end of said drum, a tube mounted in said casing in spaced relation- 115
- 60 ship from said first mentioned portion thereof, a sleeve mounted within said tube, said sleeve and said tube being closed at their ends and having slots adapted to be aligned by rotation of said sleeve, means for supply- 120
- 65 ing viscous liquid to the interior of said 125
- 130

In testimony whereof I affix my signature. 80
JOHN E. JOHNSON.
